UNITED STATES PATENT OFFICE

CLEMENT BROWN, OF WITTON, BIRMINGHAM, ENGLAND, ASSIGNOR TO AMALGAMATED CARBURETTERS LIMITED, OF BIRMINGHAM, ENGLAND

CARBURETOR

Application filed March 3, 1927, Serial No. 172,531, and in Great Britain May 25, 1926.

This invention comprises certain improvements in or relating to the mixture supply of internal combustion engines, and it refers particularly to that type of mixture supply system wherein an auxiliary air inlet is provided in association with the jet in manner such that a rich mixture is delivered into the induction pipe or other region of negative pressure.

10 Primarily the present invention comprehends means for automatically regulating this auxiliary air inlet by or in conjunction with the operation of the control valve.

In order that this invention may be clearly understood and readily carried into practice reference may be had to the appended 15 sheet of explanatory drawings, on which

Figure 1 is a plan view of a carburetor incorporating one embodiment of the present 20 invention.

Figure 2 is a view similar to Figure 1 but illustrating a modified form of the present invention.

Figure 3 is a sectional elevation showing 25 the auxiliary air passages of the carburetor shown in Figure 1, the auxiliary air inlet being closed.

Figure 4 is a similar view to Figure 3, but with the auxiliary air inlet open.

20 In the embodiment of the present invention shown in the drawings the reference letter *a* designates a surface of the carburetor body at which we arrange the inlet port or opening of the auxiliary air inlet conduit appertaining to the jet. This auxiliary air inlet conduit may be associated with the jet according to any orthodox methods, and if desired a constriction may be incorporated in the conduit. *b* is a lever which is provided 25 with a closure pad *c* adapted to close the auxiliary air inlet conduit at the face *a*. This lever *b* which may comprehend a strip of sheet metal may be formed to a socket configuration *d* designed to embrace the spindle *e* of the main throttle valve. Between this spindle *e* and the socket *d* a frictional engagement is provided. The member *b* is capable of an angular movement limited on the one hand by the face containing the auxiliary air inlet conduits at *a* and on the other

hand by any suitable abutment such as that indicated by the reference letter *f*. As shown in Figure 1, therefore, throughout the range of movement of the throttle valve any closing movement of the throttle valve has the 55 result that it opens the auxiliary air inlet port at *a* while any opening of the throttle valve has the effect of closing the said air inlet port *a*. In the plan view shown in Figure 1 it should be explained that the throttle valve 60 opens by a clockwise movement, and it will be appreciated that the function of the member *b* in nowise interferes with the ordinary operation of the throttle valve. The throttle valve operates as usual with the exception 65 that regardless of its position any movement in opening closes the auxiliary air inlet at *a*, while any movement in closing opens the auxiliary air inlet port at *a*, the arrangement 70 being such that a continuation of movement 75 of the throttle valve still leaves the member *b* in its position until there is a reversal of this movement.

A convenient float feed may be incorporated 80 comprising a float chamber *j* Figures 3 and 4 adapted to supply fuel by way of a fuel 75 passage *k* to a removable jet member 1 having a central air inlet *m*. Said jet member 1 is reduced in diameter to form in conjunction 85 with the adjacent wall of the carburetor an annular chamber *n* where rich mixture is produced and from which the rich mixture passes by way of a duct *o* to an annular chamber *p* surrounding the choke tube *q*. *r* is the main air inlet of the carburetor. The lever *b* carries a leather or other closing pad *c* arranged to coact with the auxiliary air inlet port *a* which communicates with a vertical air passage *s* leading into the annular chamber *p* before referred to. In Figure 3 the closure 90 pad *c* is shown in a closed position as when the throttle has executed an opening movement and in Figure 4 the pad *c* associated with the lever *b* is shown in the open position limited by the stop *f* in which air is admitted 95 through the inlet *a* for the purpose of increasing the proportion of air when the throttle valve executes a closing movement.

Since it may be desirable to provide that when the throttle valve is in its nearly closed 100

or idling position the inlet to the auxiliary air conduit at a is closed contrary to the conditions obtaining in the embodiment shown in Figure 1, we may alternatively employ a mechanism one embodiment of which is illustrated in Figure 2 in which g is the throttle valve spindle frictionally carrying the member b' which fulfills a function similar to that described in connection with Figure 1, but in the embodiment shown in Figure 2, the throttle valve spindle g is provided with an additional arm h which co-operates with the lever i in such manner that when the throttle valve is in its nearly closed or idling position as shown in Figure 2, through the intermediary of this lever i the member b' is caused to close the auxiliary air inlet at the face a' . So soon as any substantial opening of the throttle occurs the lever i no longer functions, while upon closing of the throttle valve when in an open position the member b' is automatically displaced to open the supplementary air inlet at a' , the frictional engagement between the throttle spindle g and the member b' being sufficient to overcome any resistance which might occur as a result of the lever i .

Having described my invention, what I claim and desire to secure by Letters Patent is:—

1. In combination with a carburetor having an air passage, said passage having a main air inlet, an auxiliary air inlet, and an air outlet; a throttle controlling said outlet and having a spindle, a lever secured to said spindle for movement by said spindle, a closure arranged on said lever and adapted to close said auxiliary air inlet when the spindle is turned in the required direction to open the throttle valve and to open said air inlet when said spindle is turned in the reverse direction and means coacting with, said lever to open or close said auxiliary air inlet on a very slight movement of the throttle.
2. The carburetor as claimed in claim 1, in which the means coacting with the lever comprises a tappet arm on the throttle spindle and a second lever arranged to bear on the first named lever and having a tappet arm arranged in the path of and for operation by the first named tappet arm.
3. In combination with a carburetor having an auxiliary air inlet duct which communicates directly with the main choke tube, a throttle having a spindle and means actuated by the throttle to close or open said auxiliary air inlet duct according to the direction in which the throttle is moved, said means comprising a closure carried by a lever, which lever is mounted on the spindle and has frictional contact therewith, so that the lever is moved by an initial movement of the spindle and the spindle may be further moved independently of the lever.
4. A carburetor as claimed in claim 3, in

which the throttle has a spindle and in which the controlling means for the auxiliary air inlet duct is a closure carried by a lever, which lever is mounted on the spindle and has frictional contact therewith, so that the lever is moved by an initial movement of the spindle and the spindle may be further moved independently of the lever.

In witness whereof I affix my signature.
